STACKING STOCK BASKET

John P. Moorhead, Dearborn Township, Wayne County, Mich., assignor to Wall Wire Products Company, Plymouth, Mich., a corporation of Michigan

Application June 16, 1950, Serial No. 168,637

10 Claims. (Cl. 220—19)

1 This invention relates to stock baskets in general and has particular reference to stock baskets of wire construction having means provided thereon whereby a plurality of such baskets may be stacked vertically so that relative movement between adjacent baskets in the stack is prevented.

The invention comprises a basket having upper and lower frame members and a closed loop member secured to the lower frame and providing a part of the bottom of the basket, the upper frame being provided with upwardly offset portions defining handles engageable with the loop member of a superposed basket of like construction.

A principal object of the invention, therefore, is to provide a stock basket constructed so that a plurality of such baskets may be stacked vertically.

A further object of the invention is to provide a new and efficient stacking arrangement for stock baskets.

Another object of the invention is to provide a stacking stock basket which is comprised of a minimum number of parts and which is simple in construction and inexpensive to manufacture.

Other and further objects of the invention will be apparent from the following description and claims and may be understood by reference to the accompanying drawings, of which there are two sheets, which by way of illustration show preferred embodiments of the invention and what I now consider to be the best mode in which I have contemplated applying the principles of my invention. Other embodiments of the invention may be used without departing from the scope of the present invention as set forth in the appended claims.

In the drawings:

Fig. 1 is a perspective view of a stock basket embodying my invention;

Fig. 2 is an end elevational view of two of the baskets shown in Fig. 1 arranged in stacked relation;

Fig. 3 is a top plan view of the basket disclosed in Fig. 1;

Fig. 4 is a side elevational view of an assembly of baskets, with certain portions thereof shown in section; and

Fig. 5 is a fragmentary perspective view of a modified form of the invention.

Referring more particularly to the drawings, there is disclosed in Fig. 1 a stock basket embodying my invention which is comprised of a

top frame 10, a bottom frame 12, and upright support members 14 secured to each of the frames 10 and 12 so as to maintain the frames in spaced, parallel relation. The frames 10 and 12 may be made of wire and are rectangular in shape. The frames 10 and 12 are of substantially the same width, but the upper frame 10 is longer than the lower frame 12. As disclosed in Fig. 3, the distance between the outer surfaces of the frame 12 is approximately equal to the distance between the inner surfaces of the frame 10.

An elongated, closed loop 16 of wire is secured to the frame 12 at opposite ends thereof. The loop 16 is arranged in the plane of the frame 12 and provides a part of the bottom of the basket. A wire strip 18 extends between the opposite ends of the frame 12 and also provides a part of the bottom of the basket. The members forming the bottom of the basket may vary in number and in size from those disclosed herein so as to accommodate the particular article to be carried by the basket.

The ends of the loop 16 are bent upwardly as at 20 so as to extend across the top of the ends 22 of the frame 12. The loop 16 and the support members 14 may be secured to the frames by welding or in any other suitable manner. The ends 22 of the loop 16 project outwardly beyond the ends of the frame 12 and are spaced therefrom a distance slightly greater than the thickness or diameter of one of the frame members.

The upper frame 10 at each of the ends thereof is upwardly offset so as to define transversely extending handles 24. The handle portions 24 are connected to the frame 10 by upwardly converging portions 26. The upwardly offset portions of the frame 10 extend vertically above the frame 10.

The offset portions of the upper frame 10 provide handles for handling the basket and also provide a part of the stacking means provided on the basket. As disclosed in Figs. 2 and 4, a plurality of the baskets disclosed herein may be stacked vertically with the lower frame 12 of the upper basket seated upon the upper frame 10 of the lower basket. The upwardly offset portions 24 of the top frame 10 of the lower basket are adapted to be engaged by the projecting portions 22 of the loop 16 of the upper basket so as to prevent relative lateral and endwise movement between the baskets. The outwardly projecting portions 22 of the loop 16, together with the adjacent ends of the frame 12, define elongated slots arranged in the vertical plane of the ends of the upper

frame 10 for receiving the upwardly offset portions of the next lower basket.

When the baskets are arranged as shown in Figs. 2 and 4, the inner surfaces of the projecting portions 22 of the upper basket engage the upwardly converging portions 26 of the frame 10 of the lower basket so as to prevent relative lateral movement between the baskets. The inner surfaces of the upwardly offset portions of the frame 10 of the lower basket are engageable with the outer surfaces of the ends of the frame 12 of the upper basket for preventing relative endwise movement between the baskets.

In Fig. 5 there is disclosed a modification of my invention wherein the closed loop member 116 is flat throughout its length and the ends of the lower frame 12 are upwardly offset or recessed in order to accommodate the projecting ends of the loop 116. In this modification the loop 116 is also arranged in the plane of the bottom frame 12 and provides a part of the bottom of the basket. The strip 18 in this instance is secured to the under side of the recessed portions of the ends of the frame 12. The structure of the basket is otherwise similar to that previously described and the stacking arrangement is substantially the same as in the previous modification.

The vertical support members 14 disclosed herein form no part of the present invention, and the top and bottom frames 10 and 12 may be secured in spaced, parallel relation in any suitable manner.

While I have illustrated and described preferred embodiments of my invention, it is understood that these are capable of modification, and I therefore do not wish to be limited to the precise details set forth but desire to avail myself of such changes and alterations as fall within the purview of the following claims.

I claim:

1. A basket structure comprising superposed baskets each having top and bottom frame members arranged in spaced, parallel relation and a closed loop member secured to said bottom frame and projecting beyond and spaced from opposite ends thereof, said top frame member at opposite ends thereof being deformed so as to define upwardly offset integral handle portions overlying the space between said bottom frame and the projecting portions of said loop member so as to be engageable with the projecting portions of the loop members of the next upper basket thereby preventing relative endwise and lateral movement between said baskets.

2. A basket structure comprising superposed baskets each having top and bottom frame members arranged in spaced, parallel relation and a closed loop member secured to said bottom frame and projecting therebeyond at opposite ends thereof, said top frame member at opposite ends thereof being deformed to provide upwardly offset handle portions, said deformed portions being arranged above the space between said projecting portions of said loop member and said ends of said bottom frame, so as to be engageable with the inner surfaces of the projecting portions of the loop member of the next upper basket so as to prevent relative endwise and lateral movement between said baskets.

3. A basket structure comprising superposed baskets each having top and bottom frame members arranged in spaced, parallel relation and an elongated wire member defining a closed figure secured to said bottom frame and having por-

tions thereof spaced outwardly from said bottom frame at opposite ends thereof, said top frame member at opposite ends thereof being formed to provide upwardly offset portions overlying the space between said bottom frame and said outwardly spaced portions of said wire member so as to be engageable with the outwardly spaced portions of the wire member of the next upper basket for preventing relative endwise and lateral movement between said baskets.

4. A basket structure according to claim 3 wherein said elongated wire member provides a part of the bottom of the basket.

5. A basket structure comprising superposed baskets each having rectangular top and bottom frame members arranged in spaced, parallel relation, and an elongated closed loop member secured to the upper surface of said bottom frame and projecting beyond said frame at opposite ends thereof so as to define elongated retaining slots at said ends, said loop member being arranged in the plane of said bottom frame and providing a part of the bottom of the basket, said top frame member at opposite ends thereof being deformed to provide upwardly offset transversely extending portions overlying said slots so as to be receivable within the slots of the next upper basket so as to prevent relative endwise and lateral movement between said baskets.

6. A basket structure comprising superposed baskets each having top and bottom frames arranged in spaced, parallel relation and a member providing a part of the bottom of said basket comprising a closed loop arranged in the plane of and secured to the lower surface of said bottom frame at opposite ends thereof, said bottom frame at said opposite ends being upwardly offset to accommodate said loop member, said loop member having portions thereof projecting outwardly of and spaced from said opposite ends of said bottom frame, said top frame member at opposite ends thereof being deformed to provide upwardly offset portions overlying the space between said ends of said bottom frame and said projecting portions of said loop members so as to be engageable with the projecting portions of the loop member of the next upper basket so as to prevent relative endwise and lateral movement between said baskets.

7. A basket structure comprising superposed baskets each having horizontal rectangular top and bottom frame members arranged in spaced, parallel relation, opposite ends of said bottom frame member being arranged inwardly of the corresponding ends of said top frame member, and a closed loop member secured to said bottom frame and having portions thereof spaced outwardly from said bottom frame at said opposite ends thereof so as to define together with said ends elongated slots each arranged in the vertical plane of one of said ends of said top frame, said top frame member at said opposite ends thereof being deformed to provide upwardly offset portions receivable in the slots of the next upper basket for preventing relative endwise and lateral movement between said baskets.

8. A stock basket comprising horizontal rectangular upper and lower frame members arranged in spaced parallel relation, and a member secured to said lower frame member and having portions projecting beyond said frame at opposite ends thereof, said projecting portions and said ends defining retaining slots, said upper frame member at opposite ends thereof being deformed to provide upwardly offset portions terminating in

horizontally extending handles overlying said retaining slots, said offset portions being receivable in the retaining slots of a superposed basket of like construction.

9. A basket structure comprising superposed baskets each having rectangular upper and lower frame members arranged in spaced parallel relation, said upper frame member being longer than said lower frame member, said upper frame member at the ends thereof being deformed to provide 10 upwardly offset portions, and means on said lower frame cooperable with said lower frame to define therewith closed loops projecting outwardly of said ends of said upper frame and arranged for overlapping engagement with the upwardly 15 offset portions of the next lower basket for preventing relative movement between said baskets.

10. A stock basket comprising spaced rectangular upper and lower frame members, said upper frame being longer than said lower frame, and 20 an elongated closed loop member secured to said lower frame at the ends of said frame, said loop

member providing a part of the bottom of the basket and having portions thereof spaced outwardly of said ends of said lower frame, said upper frame member at the ends thereof being deformed to provide upwardly offset portions adapted to be received between the outwardly spaced portions of the loop member and said opposite ends of the lower frame member of a superposed basket of like construction.

JOHN P. MOORHEAD.
